UNITED STATES PATENT OFFICE.

FREDERICK WINK, OF PHILADELPHIA, PENNSYLVANIA, ASSIGNOR TO
THOMAS DOLAN AND R. WILLIAMS, OF SAME PLACE.

DESIGN FOR SHAWL.

Specification forming part of Design No. 6,405, dated February 11, 1873.

To all whom it may concern:

Be it known that I, FREDERICK WINK, of the city and county of Philadelphia, State of Pennsylvania, have invented a Design for a Shawl-Pattern, of which the following is a specification:

The figure in the accompanying drawing represents my complete design for a shawl-pattern, the remainder being merely a repetition of that which appears.

The design consists of a series of parallel stripes, of different widths and shades or colors, the majority of these stripes being plain throughout; the stripes *a* and *b* being the only exceptions. These stripes are elaborately ornamented in a manner which is too clearly

shown in the drawing to need description, the principal difference between them being that the stripe *b* is somewhat the widest.

Irrespective of the colors employed, I claim—

1. The design for the stripe *a* or *b*, as represented.

2. The design for the whole pattern, as represented in and by the accompanying drawing.

In testimony whereof I have signed my name to this specification in the presence of two subscribing witnesses.

FRED. WINK.

Witnesses:

WM. A. STEEL,
HUBERT HOWSON.
